US00D876137S

(12) **United States Design Patent** (10) Patent No.: **US D876,137 S**
(45) Date of Patent: **** Feb. 25, 2020**

(54) **FURNITURE**

(71) Applicant: **NATUZZI S.p.A.**, Santeramo in Colle (Bari) (IT)
(72) Inventor: **Claudio Bellini**, Milan (IT)
(73) Assignee: **Natuzzi S.p.A.**, Santeramo in Colle (Bari) (IT)

(**) Term: **15 Years**

(21) Appl. No.: **29/633,693**

(22) Filed: **Jan. 15, 2018**

(30) **Foreign Application Priority Data**

Jul. 13, 2017 (EM) 004101210-0049

(51) LOC (12) Cl. **06-03**

(52) U.S. Cl.

USPC **D6/691.2**

(58) **Field of Classification Search**

USPC D6/657, 659, 641, 642, 685, 686, 691, D6/691.1-691.9

CPC A47B 7/00; A47B 13/00; A47B 13/02; A47B 13/08; A47B 13/12; A47B 17/00; A47B 21/00; A47B 2200/0001; A47B 2200/0011; A47B 2200/002
